ELECTROMAGNETIC SWITCH

Korbinian Karrer, Munich, Germany, assignor to Siemens & Halske Aktiengesellschaft Berlin and Munich, a corporation of Germany

Application December 20, 1956, Serial No. 629,541

11 Claims. (Cl. 200—87)

This invention relates to electromagnetic switches and is particularly concerned with improvements in a magnetically operated switch of the general type as described in United States patent to W. B. Ellwood, No. 2,264,746, dated December 2, 1941.

The switch described in the above-noted patent comprises an evacuated or gas-filled tube containing two mutually spaced stationary positioned outer contact reeds or springs between which is disposed a third inner switch-over spring. In its normal position, the switch-over spring is in contact-making engagement with one of the outer springs which is made of non-magnetic material. The other outer spring and the inner switch-over spring are both made of magnetizable material. Upon subjecting the corresponding switch structure to the action of a magnetic field which is operative longitudinally thereof, lines of force will become active across the gap between the two magnetizable springs thus producing a force which draws the two springs together, thereby moving the inner switch-over spring from its normal position in contact engagement with one of the outer springs into contact-making engagement with the other outer spring. The spacing between the two outer springs is thereby maintained due to the provision of an insulating spacer member disposed therebetween. A contact arrangement of this kind is usually referred to as a break-make contact arrangement, having a "break" side at which the contacts are normally closed and a "make" side at which the contacts are normally open, the contact closure at the make side being effected by the actuation of the switch-over spring from its "break" to its "make" position.

It happens frequently in this type of switch that the contact-making points stick together due to overloading or contact wear. If the sticking involves the contact points in the normal position, that is, at the break side, the excitation normally required for operation will not suffice for moving the inner switch-over spring to the alternate operated or make position. A considerably stronger excitation is therefore required for this purpose because the full range of the working gap has to be overcome to move the inner switch-over spring into its alternate make position. This gap remains due to the previously mentioned spacing member unaltered to the instant when the sticking at the break side is overcome at which instant the inner switch-over spring is displaced to move for contact closure to the make side.

The object of the invention is to reduce as far as possible the detrimental effect of the sticking of the contact points which generally cannot be altogether avoided. The invention overcomes this defect by positioning the outer contact spring related to the make side and provided for cooperation with the inner switch-over spring in the make or working position thereof, operatively and resiliently with respect to the other stationary outer spring provided for cooperation with the switching spring in the normal or break position thereof.

The various objects and features of the invention will

2

appear from the description of embodiments which will be rendered below with reference to the accompanying drawings.

Referring to the drawings:

5 Figs. 1a to 1c show the arrangement of a break-make contact embodiment in various switching positions thereof; the contact-making end of the outer spring coating with the switch-over spring in the normal or break position thereof being made of non-magnetic material;

10 Fig. 2 illustrates a break-make contact embodiment wherein the entire outer spring at the break side is made of non-magnetic material;

15 Figs. 3a to 3c indicate various switching positions of a simple break contact arrangement according to the invention; and

20 Figs. 4 to 6 show break-make contact arrangements according to the invention wherein the switch-over spring and the outer contact spring at the break side extend from one end of the contact envelope or tube inwardly therefrom while the outer spring at the make side extends from the other end of the tube inwardly thereof.

25 Referring now to Figs. 1a to 1c, Fig. 1a shows the contacts in the normal position. The tube may be a glass tube fused at its opposite ends as indicated at 1.

30 Fused into one end of the tube are the two outer contact springs 2 and 3 and fused into the other end of the tube is the inner switch-over spring 4. The contact-making end of the outer spring 3, which is relatively rigid, is made of non-magnetic material as indicated by the hatching thereof. The contact-making end of the yieldable inner switch-over spring 4 is disposed between the two outer springs 2 and 3, such end being normally in break contact-making engagement with the spring 3. The two contact springs 2 and 4 are made of magnetizable material.

35 Upon subjecting the switch arrangement to a magnetic field acting longitudinally thereof, lines of force will become operative across the gap between the springs 2 and 4 causing displacement of the spring 4 in the direction of spring 2, thus breaking the contact engagement between springs 3 and 4 (break side), shown in Fig. 1a, and closing contact between springs 4 and 2 (make side) as shown in Fig. 1b. Upon cessation of the magnetic excitation, the contact spring 4 will flex back to initial position into normal break contact-making engagement with spring 3.

40 If sticking should occur between the springs 3 and 4, the gap between such springs will be reduced upon normal magnetic excitation due to radial inward flexing of the contact-making end of spring 2 as indicated in Fig. 1c, such spring being for this purpose operatively and resiliently positioned as noted before. The magnetic field now active across the reduced gap will suffice to effect operative actuation of the spring 4 to alternate make position.

45 It must be considered in this connection that the magnetic flux is inversely proportional to the magnetic impedance represented essentially by the working gap. The magnetic force is however directly proportional to the square of the flux. It follows, therefore, that the attractive force increases with the square of the reduction of the spacing between the corresponding springs.

50 The advantage of the switch arrangement according to the invention resides in the fact that, due to the resilience of the spring 2, the magnetic excitation required for the operation of the switch-over spring need not exceed normal excitation.

55 The spring 2 may be made stiffer than the spring 4 in order to secure actuation of the latter responsive to normal magnetic excitation.

60 It is understood, of course, that the entire spring 3 may be made of non-magnetic material as indicated in

65

70

Fig. 2. However, the choice of the material for the springs also depends upon other conditions, for example, upon the fusibility of the corresponding material with the glass tube.

The above described embodiment, concerned with a break-make contact switch arrangement may of course also be utilized in the case of a simple break contact structure. It is for this purpose merely necessary to avoid using the outer contact spring cooperating with the inner switching spring in the working position thereof as a spring which is operative in a circuit, or omitting a terminal therefor extending to the outside of the glass tube.

A contact switch arrangement of this kind is shown in Figs. 3a to 3c. This embodiment corresponds largely to the embodiment illustrated in Figs. 1a to 1c except that the spring 2 has no terminal leading to the outside, being held in position by a mounting member 5. The operation corresponds essentially to that described in connection with Figs. 1a to 1c.

Figs. 4 to 6 show a break-make contact switch arrangement having the outer contact spring 6 belonging to the break side and also the switching spring 7 extending from one end of the tube, while the outer contact spring 8 cooperating with the switching spring 7 in the actuated or make position thereof extends from the other end of the tube.

In the embodiment according to Fig. 4, all three contact springs are made of magnetizable material. The outer break contact spring 6 cooperating with the inner switch-over spring 7 in normal position thereof is fixedly or rigidly disposed and slightly bent for contacting at its end the corresponding end of the switch-over spring 7, the latter being separated from the outer make contact spring 8 by a gap.

Upon energization of the switch structure according to Fig. 4, a magnetic field will become active across the gap between the inner ends of the springs 7 and 8, drawing these springs together. The magnetic force active between the ends of the springs 6 and 7 is small as compared with the force acting between the ends of the springs 7 and 8 due to the small overlap between springs 7 and 8 as compared with the considerably greater overlap between springs 6 and 7 which causes a considerably greater inductance across the gap.

As in the previously described embodiments, the outer contact spring 8 cooperating with the inner switching spring 7, is arranged resiliently; accordingly, should sticking occur between the springs 6 and 7, the inner end of the contact spring 8 will be responsive to energization flex radially inwardly to reduce the gap, thereby causing the magnetic force to effect actuation of the spring 7.

In the switch structure according to Fig. 4, the switching spring 7 is for flexibility thinner than the outer contact spring 6 disposed immediately adjacent thereto. The arrangement reduces the magnetic impedance on the corresponding side of the structure. It is for this reason possible to considerably weaken the switching spring 7 in the vicinity of its mounting because the flux resulting in the contact actuation flows in part over the outer contact spring 6. The result is that spring 7 can be shortened while fully preserving the flexibility thereof. A shorter overall switch may in this manner be made.

An example of such a shorter switch is shown in Fig. 5. The spring 7 is cross-sectionally reduced or weakened immediately adjacent its fusion in the tube end.

In the normal position, the contacting surfaces between the springs 6 and 7 are very small, resulting upon energization in a certain undesired attraction of the parts due to corresponding magnetic induction. This effect may be avoided by making the inner end of the spring 6 of non-magnetic material as indicated by the hatching appearing in Fig. 6.

Changes may be made within the scope and spirit of the appended claims.

I claim:

1. In a magnetically operated switch structure having disposed within a sealed elongated tube a break-make contact spring arrangement including a first outer contact spring related to the break side and a second outer contact spring related to the make side, and having a yieldable switch-over inner contact spring operatively positioned between said first and second outer contact springs and normally in contact-making engagement with said first outer contact spring related to the break side, wherein breaking of the contact engagement between said inner spring and said first outer spring may be impeded by contact sticking; a device for reducing the effect of such contact sticking so as to assure breaking the corresponding contact engagement, said device comprising operatively and resiliently positioning said second outer contact spring related to the make side so as to cause such second outer contact spring, in case of sticking of said inner switch-over spring in contact engagement with said first outer contact spring, to flex, responsive to normal magnetic excitation, in the direction of said sticking inner contact spring, thereby reducing the air gap between such second outer spring and said sticking inner spring and consequently effecting increase of the magnetic attraction forces between these springs by an amount corresponding to the square of the reduction of the air gap, said increased magnetic attraction forces being operative to actuate said inner switch-over contact spring and thereby by breaking the sticking contact engagement thereof with said first outer contact spring.
2. A device according to claim 1, wherein said second outer contact spring is relatively stiffer than said inner switch-over contact spring.
3. A device according to claim 1, wherein the contact-making portion of said first outer contact spring is made of non-magnetizable material.
4. A device according to claim 1, wherein the contact-making portion of said second outer contact spring is made of magnetizable material.
5. A device according to claim 1, comprising a mounting member disposed upon said first outer contact spring for supporting said second outer contact spring.
6. A device according to claim 1, wherein said outer contact springs extend from one end of said tube inwardly thereof, and wherein said inner switch-over contact spring extends from the other end of said tube inwardly thereof.
7. A device according to claim 1, wherein said first outer contact spring and said inner switch-over contact spring extend from one end of said tube inwardly thereof, and wherein said second outer contact spring extends from the other end of said tube inwardly thereof.
8. A device according to claim 1, wherein said outer first and second contact springs and said inner switch-over contact spring are made of magnetizable material.
9. A magnetically operated switch structure for reducing contact sticking, comprising two outer contact springs and a yieldable switch-over contact spring operatively positioned between said outer contact springs and normally in engagement with one of the outer contact springs related to the resting side, the outer contact spring related to the working side of the contact making end of the contact spring being operatively and resiliently positioned with respect to the outer contact spring related to the resting side of the contact making end of the outer contact springs, the spring forces of the outer contact spring belonging to the working side being such that responsive to magnetic excitation in case of sticking of the switch-over spring, with the outer contact spring related to the resting side, the air gap between said last mentioned outer contact spring and said switch-over spring will be reduced upon normal reenergization and the magnetic field then active across the reduced gap will effect operative actuation of the switch-over spring to the alternate working position with an increase in the operating force being

cause of the reduction of the aforesaid air gap, and said switch-over spring is reduced in cross-section contiguous to the mounting thereof for reducing the magnetic impedance on the adjacent side of the switch structure.

10. A magnetically operated switch structure for reducing contact sticking, comprising two outer contact springs and a yieldable switch-over contact spring operatively positioned between said outer contact springs and normally in engagement with one of the outer contact springs related to the resting side, the outer contact spring related to the working side of the contact making end of the contact spring being operatively and resiliently positioned with respect to the outer contact spring related to the resting side of the contact making end of the outer contact springs, the spring forces of the outer contact spring belonging to the working side being such that responsive to magnetic excitation in case of sticking of the switch-over spring, with the outer contact spring related to the resting side, the air gap between said last mentioned outer contact spring and said switch-over spring will be reduced upon normal reenergization and the magnetic field then active across the reduced gap will effect operative actuation of the switch-over spring to the alternate working position with an increase in the operating force because of the reduction of the aforesaid air gap, said switch-over spring is reduced in cross-section contiguous to the mounting thereof for reducing the magnetic impedance on the adjacent side of the switch structure, and further weakening the switch-over spring contiguous to the aforesaid mounting thereof since the magnetic flux resulting in the contact actuation flows in part over the contiguous outer contact spring permitting the shortening of said switch-over spring and said contiguous outer contact, whereby the length of the switch structure is shortened.

11. A magnetically operated switch structure for reducing contact sticking, comprising two outer contact springs and a yieldable switch-over contact spring operatively positioned between said outer contact springs and normally in engagement with one of the outer contact springs related to the resting side, the outer contact spring related to the working side of the contact making end of

the contact spring being operatively and resiliently positioned with respect to the outer contact spring related to the resting side of the contact making end of the outer contact springs, the spring forces of the outer contact spring belonging to the working side being such that responsive to magnetic excitation in case of sticking of the switch-over spring, with the outer contact spring related to the resting side, the air gap between said last mentioned outer contact spring and said switch-over spring will be reduced upon normal reenergization and the magnetic field then active across the reduced gap will effect operative actuation of the switch-over spring to the alternate working position with an increase in the operating force because of the reduction of the aforesaid air gap, said switch-over spring is reduced in cross-section contiguous to the mounting thereof for reducing the magnetic impedance on the adjacent side of the switch structure, further weakening the switch-over spring contiguous to the aforesaid mounting thereof since the magnetic flux resulting in the contact actuation flows in part over the contiguous outer contact spring permitting the shortening of said switch-over spring and said contiguous outer contact, whereby the length of the switch structure is shortened, and said inner end of the aforesaid last mentioned outer contact spring contiguous to the end of the switch-over spring being formed from non-magnetizable material, whereby in the normal position of the aforesaid outer contact spring and the switch-over spring, the undesirable attraction of said parts due to magnetic induction is avoided even though the contacting surface between said last mentioned springs is very small.
